AUTOMATIC GAUGE VALVE

Edward M. Greer, Hempstead Township, Nassau County, N. Y., and Donald A. Stark, Chicago, Ill., assignors to Greer Hydraulics Inc., Brooklyn, N. Y.

Application January 10, 1946, Serial No. 640,238

3 Claims. (Cl. 137—153)

1

This invention relates to apparatus and a system for safely dispensing fluids at a hydrostatic pressure lower than the pressure to which the fluid supply may rise.

More particularly, this invention relates to a combined reducing valve and accumulator for use with gases, liquids and semi-liquid substances, such as greases and the like.

In fluid storage and dispensing devices, the fluid supply from a pump may rise to a relatively high pressure. For reasons familiar to those skilled in the art it is desirable that a distributing line be protected from a high pressure, or that the gauge be protected from strong pulsations of fluids or gases to be stored under a relatively high pressure. On the other hand, it is frequently quite essential that a dispensing device deliver the stored fluid to the ultimate point of use at a pressure which will never exceed a predetermined and relatively low value. Furthermore, it is often desirable that the fluid be dispensed at a substantially uniform pressure, notwithstanding that the pressure of the fluid in the main reservoir or dispensing line may vary in pressure from a relatively high value down to a relatively low value.

Apparatus of the character just described frequently takes the form of a low pressure storage chamber or accumulator, to which the fluid is admitted via a pressure regulator and from which the fluid is withdrawn when and as needed.

In apparatus of this type, generally the main regulating valve, which controls the admission of a fluid from a high pressure conduit to another conduit at a low pressure, is actuated to an open position by a piston moved with a spring and to a closed position by the high pressure fluid entering the valve, the admission of such moving high pressure fluid being governed or controlled by the resilient means whose position is affected by the pressure existing on the fluid pressure side of the regulating valve.

It is an object of this invention to provide an accurate and sensitive safety device devoid of needle valves and diaphragms and which is peculiarly suited to both open and close according to the fluid pressure prevailing in the supply line.

In the present invention there is a device in which the fluid is dispensed and kept within sufficiently close limits to satisfy the requirements for any particular use. Such apparatus is applicable to hydraulic testing equipment, to anesthetic dispensing apparatus, to dispensing lubricating oils and greases, and especially to be associated with any use wherein a gauge is to be protected from excessive pressures.

2

One object of this invention is to provide a combined reducing valve and accumulator which is relatively simple in construction, low in cost, and free from trouble.

5 Another object of this invention is to provide a reducing safety valve which will protect an approximately constant reduced pressure system from pulsations of higher pressure that may be detrimental to the apparatus in such system.

10 Still another object of this invention is to provide a fluid pressure reducing valve in which there is provided a positive seal to take up shock waves in the fluid supplied which may be produced by the sudden opening or closing of a valve in either system.

15 Another purpose of this invention is to provide a safety pressure regulator and storage device including means for maintaining a relatively constant pressure in the delivered fluid, even when 20 the consumption of such fluid is intermittent or cyclic in character, and in which the supply may also be intermittent.

25 Another purpose of this invention is to provide a combination pressure reducing valve and accumulator in which the pressure of the fluid delivered therefrom will drop from the optimum value only relatively slowly, even after the pressure of the fluid supply to the device has been closed.

30 Other and further purposes and advantages of this invention will be apparent from the following detailed specification and by reference to the hereunto appended drawings, in which:

Fig. 1 schematically illustrates one embodiment 35 of this invention, showing the reducing valve in longitudinal cross-section.

Fig. 2 illustrates a modified form of the valve plunger.

In the drawing a fluid supply line 10 is connected to a T-coupling 11. To another opening of this T-coupling is connected a gauge 12, indicating the pressure of the main fluid supply, the use of such gauge being desirable, but not necessary. To the last opening of the coupling is connected a reducing valve 9, comprising a main body portion 13, provided with a lateral passageway 14 extending completely therethrough. At the upper end of passageway 14 is another T-coupling 15, serving to supply fluid at the reduced pressure to gauge 16, and to outlet line 17. At the lower end of passageway 14 is an accumulator 18. This accumulator is preferably of the type in which the interior portion of the accumulator, not occupied at any given instant by the stored fluid, is filled by an elastic bladder

19, or other similar device, such bladder being filled with any suitable gas, such as air, via a filling opening 20, which opening is controlled by an air valve 21, after the bladder has been filled to the desired pressure. Such type of accumulator is well known in the art and is especially desirable, although not essential, when dealing with semi-fluid materials, such as greases.

Coupling 11 feeds the incoming high pressure fluid to a chamber 22. At the inward end of this chamber there is located a piston 23. A valve member 24 is firmly affixed to the piston 23 at the end of piston 23 toward chamber 22. Valve 24 seats by means of a seal 25, when it is displaced toward the left. When displaced toward the right the supply fluid passes through hollow or cutaway portions 26 and 27, so as to pass by the valve seal 25 and its seat 30, and on through a bore 28, which is of greater radius than the external periphery of the portion 23, and the fluid thus passes into passageway 14. The fluid is then passed into the accumulator 18 as well as to the gauge 16 and into the outlet line 17.

The piston 23 extends to the left of passageway 14 into a spring chamber 29. A fluidtight seal 31 is positioned around the periphery of the piston 23 to prevent fluid leakage into the spring chamber 29. However, any leakage of fluid into chamber 29 may be bled through a relatively small aperture 32 in a spring retaining member 33. To afford a communication between chamber 29 and the exterior of the body portion 13, an aperture 37 is provided in the end fitting 35. The left end of piston 23 is formed with a rounded bearing point 36. Resting against the projecting piston 23 is the spring retaining member 33, of a radius equal to the bore of chamber 29. Within the spring retaining member 33 is a helical spring 34. The rear or left end of spring 34 rests against a threadably secured end fitting 35, secured to the body 13. Lateral movement of element 33 to the left is brought about via piston 23 and valve 24 when the fluid pressure acts upon the valve face, such movement serving to compress spring 34.

The operation of this device is as follows: Spring 34 is arranged to exert upon valve 24 a pressure to not only open the valve 24, but to retain it open against the hydrostatic pressure exerted upon the face of valve 24 by the supply pressure fluid, until that pressure reaches a predetermined maximum setting on the gauge 16, upon which element 33 will be moved to compress the spring 34 and the hydrostatic pressure will close the seal 25 against the valve seat 30. When the fluid pressure in supply line 10, indicated by gauge 12, falls below a predetermined maximum value allowable in line 17, the reduced pressure of this fluid on valve face 24, which communicates via passageway 32 to the supply line 10, will cause the spring 34 that has been compressed to overcome the hydrostatic pressure on the face of valve 24. Accordingly, the expansion of spring 34 acts via piston 23 to push valve 24 to the right and thus open, allowing the reduced fluid supply pressure to be again charged into the bore 14 and its component connections.

The closure of the valve is again effected when the pressure in the supply line 10 has built up to a value sufficient to compress spring 34, within member 33. Movement of member 33 toward the left causes valve 24 to move in the same direction, owing to the higher pressure fluid acting

upon the face of valve 24. This movement causes the valve seal 25 to seat on the valve face 30, so that no more high pressure fluid enters bore 14.

5 A pressure wave or surge therein, will immediately communicate with element 23, which protects by means of valve 24 the gauge 16, only to open when the surge pressure has become equalized. The reason that this invention protects 10 such apparatus, is that the pressure wave must pass via the relatively sensitive valve 24 into a bore 14 that is also connected to a storage device 18. The result is that the effect of the pressure wave is substantially completely eliminated by the time such wave reaches gauge 16 15 and line 17.

While this device has been illustrated with an 20 accumulator 18, the bladder 19 of which will serve to maintain the desired pressure in the line 17 for a relatively great period of time, without the 25 injection therein of fluid from the supply pressure side of the system, it is possible in some instances to dispense with accumulator 18, when the fluid supply line pressure is cyclic or, in other words, when the fluid supply pressure continually rises and falls to provide intermittent periods of supply fluid through the reducing valve 9.

Reference is now made to Fig. 2 where valve 30 plunger 23, constituting the piston of the device, is shown provided with an ancillary fluid passageway, by-passing the main valve when the latter is closed. Such by-passing takes place only under certain conditions of relative fluid pressure at different portions of the system.

35 In Fig. 2, a relatively small bore duct 50 extends from the surface of plunger 23 which is opened to the incoming fluid. Duct 50 is terminated at the other extremity by a larger bore fluid passageway 51, the opening between 40 elements 50 and 51 being sealed, under certain conditions, by a ball-like valve member 52. Passageway 51 is extended longitudinally through the body of plunger 23 until it reaches a point in this plunger opposite passageway 14. At this 45 point, passageway 51 changes its direction through an angle of approximately 90°, then proceeding transversely through the body of plunger 23, until it reaches a point upon the surface of this plunger which is open to the fluid within passageway 14.

50 The operation of the modified valve plunger or piston shown in Fig. 2 is as follows:

When the fluid pressure of the supply has 55 reached the point where the plunger 23 is seated in the main valve seat so that fluid cannot pass therethrough from the main supply system into the accumulator system, the passage of fluid between the main supply and the accumulator system just described, this latter passage of fluid 60 being terminated by the relative pressures exerted upon the respective surfaces of ball-like element 52, which are presented to the fluid within duct 50 and to the fluid within passageway 51. If the fluid pressure in duct 50 is sufficient 65 to cause a longitudinal movement of valve element 52 so that the aperture between duct 50 and passageway 51 is unsealed, fluid will then pass via elements 50 and 51 in the accumulator system. When the pressure in the accumulator system has risen so as to exert upon element 52 a sufficient pressure to force it into the mouth of duct 50, fluid transmission between the high and low pressure systems will be terminated. As 70 fluid is withdrawn from the accumulator or low-

pressure side of the system, the diminished pressure upon valve element 52 will again allow lateral movement of this valve element, thus causing the unsealing of valve 58 and the re-establishment of fluid flow into the accumulator system.

From the foregoing description, it can be seen that the modified valve of Fig. 2 will allow the accumulator system to be recharged from the high pressure system, even though this latter system contains fluid under a pressure sufficiently great to close the main plunger valve. This ability to obtain a fluid charge under conditions just the reverse of those permitting a fluid charge via the main valve, combined with the automatic prevention of pressure in the accumulator system in excess of a predetermined amount, constitutes one advantage of the modified form of this invention shown in Fig. 2.

While we have shown one preferred embodiment of our invention in the drawing, it will be understood that various modifications may be made within the scope of this invention and it is not intended to limit the invention to this particular form.

What is claimed is:

1. A valve for supplying a low pressure system from a system carrying fluid under varying higher pressures, including a passageway connecting said two systems, a plunger valve movable to control the opening in said passageway, spring means urging said plunger valve to an open position allowing fluid to flow through said passageway, and piston means for urging said plunger valve to a closed position in said passageway, said piston including an ancillary fluid passageway extending through the body of said plunger valve between said two pressure systems, and valve means closing said ancillary passageway when the fluid pressure in said low pressure system increases to a predetermined value, whereby said low pressure

system can be charged from said variable pressure system when the pressure in said latter system is above a minimum value with respect to the pressure in said low pressure system.

- 5 2. A valve according to claim 1, in which said plunger valve has two surfaces of differing areas exposed respectively to said systems, and means to open and close said valve with the differential between the respective pressures of said systems, 10 means to close said ancillary passageway to retain the charge in said low pressure system when said differential is reduced to a predetermined minimum value, and means to open said ancillary passageway when said differential exceeds said minimum value to allow said low pressure system to be charged.
3. A valve according to claim 1, additionally including a fluid accumulator at all times actively connected to said low pressure system, whereby 15 the pressure in said latter system is held substantially constant for a limited time, notwithstanding withdrawal of fluid therefrom.
